UNITED STATES PATENT OFFICE

100,095

DESIGN FOR A GAME BOARD

Oliver H. Eriksen and Clarence M. Eriksen,
Chico, Calif.

Application April 3, 1936, Serial No. 61,939

Term of patent 7 years

To all whom it may concern:

Be it known that we, Oliver H. Eriksen and Clarence M. Eriksen, citizens of the United States, residing at Chico, in the county of Butte and State of California, have invented a new, original, and ornamental Design for a Game Board, of which the following is a specification, reference being had to the accompanying drawing, forming a part thereof.

The figure is a plan view of a game board, showing our new design; the article being of no appreciable thickness.

We claim:

The ornamental design for a game board, as shown and described.

OLIVER H. ERIKSEN.
CLARENCE M. ERIKSEN.
